UNITED STATES PATENT OFFICE.

ALEXANDER N. TURNQUIST, OF GLENELLYN, ILLINOIS.

GARMENT FASTENER.

1,424,953.

Specification of Letters Patent. Patented Aug. 8, 1922.

Application filed May 23, 1921. Serial No. 471,565.

To all whom it may concern:

Be it known that I, ALEXANDER N. TURNQUIST, a citizen of the United States, and a resident of Glenellyn, in the county of Du⁵ page and State of Illinois, have invented certain new and useful Improvements in Garment Fasteners, of which the following is a full, clear, and exact description.

The invention relates to devices adapted to be used on garments in lieu of buttons. Its object is to provide an improved device of this character which is simple in construction, can be produced at a low cost and which will hold a part as securely as a button does.

The invention consists in the several novel features hereinafter set forth and more particularly defined by claims at the conclusion hereof.

20 In the drawing: Fig. 1 is a perspective of a portion of a pair of trousers embodying the invention. Fig. 2 is a perspective of the fastening device.

The invention is exemplified in a device 25 which, in its entirety, is formed of a strip of wire and comprises prongs or sharp pointed hooks *a* which are adapted to pass through the garment, upwardly and inwardly inclined legs or members *b*, which 30 are looped forwardly, as at *c*, and an intermediate substantially circular portion *d* disposed forwardly of the members *b*. The prongs of hooks *a* are adapted to extend forwardly through the garment while the legs 35 or members *b* are disposed inside of the gar-

ment and the loops *c* are adapted to extend over the margin of the garment. The circular portion *d* is adapted to pass through a slit *e* in suspender *f*. The loops *c* are disposed closely together, so as to pass through a button-hole and the pendant circular portion or loop, being of considerable width, securely prevents any detachment of the suspender from the fastening device. By using 40 forwardly extending hooks *a*, the stresses 45 are advantageously applied to the garment, so that movement of the fastening device, resulting from movement of the body, will not disconnect the hooks or prongs *a* from the garment.

50 The invention is not to be understood as restricted to the details set forth, since these may be modified within the scope of the appended claim, without departing from the spirit and scope of the invention.

Having thus described the invention, what I claim as new and desire to secure by Letters Patent, is:

A garment fastener formed of a strip of metal and comprising hooks adapted to pass 60 through a garment, upwardly extending members between the hooks to lie at the inside of the garment, and a downwardly extending loop joined to said members at their upper ends and disposed at the outside of the 65 garment and in front of said members, said hooks extending forwardly from the members towards the loop and upwardly at the outer side of the garment.

ALEXANDER N. TURNQUIST.
